UNITED STATES PATENT OFFICE.

LEWIS WITKOWSKY, OF NEW YORK, N. Y.

BUTTON-FASTENER.

SPECIFICATION forming part of Letters Patent No. 426,350, dated April 22, 1890.

Application filed December 27, 1889. Serial No. 335,129. (No model.)

To all whom it may concern:

Be it known that I, LEWIS WITKOWSKY, a citizen of the United States, residing at New York, in the county and State of New York, 5 have invented new and useful Improvements in Button-Fasteners, of which the following is a specification.

This invention relates to improvements in button-fasteners; and the invention consists 10 in the details of construction set forth in the following specification and claims, and illustrated in the accompanying drawings, in which—

Figure 1 is a side elevation of a button- 15 fastener sectioned along xx , Fig. 2. Fig. 2 is a section along yy , Fig. 1. Fig. 3 is a side elevation of a button-fastener with the hook swung open on its hinge. Fig. 4 is an inverted plan view of a button-fastener.

20 In the drawings, the letter A indicates a base or washer, having attaching prongs or points B. The hook C has its shank D passed through a suitable eye in the washer, and the shank-head E prevents the hook becoming 25 disengaged from the washer, while leaving the hook C free to turn or swivel.

The eye or shank F of the button G is engaged by the hook C and secures the button in place. The swivel-hook C enables the button 30 to be readily turned or twisted by a button-hook or otherwise without risk of twisting the button off.

The washer A is arched or recessed, as shown, so that when the washer is secured in place— 35 as, for example, to the leather or material H of a shoe—a certain space is left between the material H and the washer, thus leaving the shank-head E and hook C free to swivel or

turn. By providing the hook C with a hinge or joint I the hook C can be readily opened, 40 Fig. 3, to detach a button, or closed, Fig. 1, when a button is to be held in place.

This button-fastener has the advantage that it is readily put in place without requiring any skilled labor for such putting in place, 45 and a button can be readily secured to or removed from the fastener without its being necessary to disturb the fastener or the material to which the fastener is attached. If one or more buttons should become chafed or 50 injured, they can thus be readily removed and replaced by others whenever desired.

What I claim as new, and desire to secure by Letters Patent, is—

1. A button-fastener consisting of an arched 55 washer having rigidly-attached prongs to enter the material from the outside and secure said washer thereto, a hook comprising a closed eye for engaging and retaining a button-shank, and a shank having a head and 60 swiveled in the washer, substantially as described.

2. The button-fastener herein described, consisting of a swivel-hook C, having a hinge or joint I, in combination with a base or 65 washer A, having attaching-prongs, said base or washer being arched or recessed to give room for the swiveling of the hook C, substantially as described.

In testimony whereof I have hereunto set 70 my hand in the presence of two subscribing witnesses.

LEWIS WITKOWSKY.
